REFLECTING OPTICAL SYSTEM

Henry Phelps Gage, Corning, N. Y., assignor to
Corning Glass Works, Corning, N. Y., a corpora-
tion of New York

Application May 15, 1933, Serial No. 671,213

8 Claims. (Cl. 88—82)

This invention has for its object to provide an optical system applicable to reflecting signals and signs in which light falling on the anterior face thereof is reflected back by the system to an ob- 5 server stationed adjacent to the line adjoining the light source of the system, giving the appear- 10 ance of illumination to the sign or signal.

The invention is characterized by the use of two lenses oppositely disposed in respect to each other, 15 at a distance apart less than the focal length of either lens with the posterior surface of the second lens planar and silvered or otherwise rendered reflecting. A plurality of such systems may be assembled in a unitary structure by forming 20 lenticular bosses, constituting lenses on one face of a disc of glass, (which disc may be planar) and assembling two such discs reversely in a suitable frame with the bossed faces opposite each other and silvering or otherwise rendering reflect- 25 tive the outer face of one of such discs. This results in a unitary structure having a smooth anterior face which is of importance in preventing the collection of dirt and snow thereon. The construction just suggested is moreover economi- 30 cal to manufacture in that it permits the construction of a sign of relatively large area from two pressed discs of glass which may be identical in contour and one of which is rendered reflect- 35 tive.

For convenience I will use the term "silvered" in this specification to define a surface rendered reflecting by silvering or any other approved manner.

Referring to the accompanying drawing in 35 which corresponding parts are designated by corresponding marks of reference.

Figure 1 is an elevation of the interior face of a disc suitable for use in a system such as is here disclosed.

Figure 2 is a vertical section through two discs such as shown in Figure 1, when assembled in a suitable frame with the outer surface of the posterior disc silvered.

Figure 3 is a diagram illustrating the path of 45 a ray through lenses of a system such as shown in Figure 2 when the incident ray is parallel with the principal axis of the system.

Figure 4 is similar to Figure 3 but showing the course of rays oblique to the principal axis of the 50 system.

As shown in Figures 1 and 2 the complete unit consists of two discs of glass A and B and each having a flange a or b surrounding it, offset from its plane. These discs are assembled in a suitable 55 frame C, the discs being reversely mounted in

the frame and spaced apart a suitable distance by the washer F. One of the discs B which will be hereinafter termed the reflecting disc has its outer surface silvered as at D. The other disc A will be termed the transparent disc. Both discs have on their interior surface a series of lenticular bosses E, forming lenses, which for efficiency should be as closely together on such surfaces as is possible. The discs may be counterparts of each other except for the silvering of the 10 posterior disc. By preference each of the discs A and B has formed therein on the periphery of its flange a slot c or d so that by bringing these slots into registration with each other in the assemblage a boss on the one disc will be in line 15 with the boss on the other disc.

Two aligned bosses with the mirror backing in line therewith constitutes a complete optical system which, as is shown in Figures 2, 3, and 4, is composed of two plano convex lenses spaced 20 from each other by a distance less than the focal length of a boss, and a mirror surface, the mirror surface being the planar face of the posterior lens situated at approximately the 25 principal focal point of the doublet formed by the two lenticular bosses. Under such conditions a ray M incident on the anterior face of the transparent face of the transparent disc A parallel with the principal axis of the system and adjacent to such axis (see Figure 3) enters the 30 disc A without suffering refraction, is refracted by the curved surface of the boss towards the principal axis, and enters the second disc B without being refracted by the curved surface of the 35 boss E carried thereby. Since the ray was bent toward the axis by the curved surface of the boss E on the disc A and was not refracted upon entering the disc B, it becomes evident that it will cross the axis at some point in the rear of the plate A. By proper adjustment of the 40 thickness of the washer F the silvered surface of the plate B may be caused to intersect the axis at the point where the ray M crosses it and hence the ray M will be reflected back through the disc B on the side of the axis opposite that 45 which it entered and will emerge from the system as ray M' substantially parallel with the axis as shown in Figure 3.

A ray N from an oblique incident bundle will 50 strike the plain outer surface of the disc A, suffer refraction as it enters the disc and be again refracted as it leaves the disc. Passing on toward the disc B the ray N is again refracted by the front curved surface of the boss E on the 55

disc B and entering the disc B is bent toward the reflecting surface D from whence it is returned through the disc B and is again refracted by the curved surfaces of the bosses E and the flat face 5 of the disc A so that it finally emerges as ray N' substantially parallel with the axis of the oblique bundle.

In actual practice I have found that when two discs of identical construction are made from 10 a glass having a refractive index of 1.50 the most satisfactory results are obtained when they are assembled with the bosses E of one plate facing the bosses E of the other plate and the distance S between the plates lies within the limits 15 shown in the following formula in which R is the radius of curvature of the bosses E and .9 R is the thickness of the plates, then

$$S = .9R \pm .1R$$

20 While in the foregoing I have shown and described the preferred embodiment of my invention, it is to be understood that minor changes in the details of construction, combination and arrangement of parts may be resorted to without departing from the spirit and scope of my invention as claimed.

Having thus described my invention what I claim and desire to secure by Letters Patent is:

30 1. A reflecting system including two cooperating oppositely disposed converging lenses, one of the lenses having both surfaces transparent and the other lens having a transparent curved surface and a plane reflecting surface which intersects the principal axis of the system at its principal focus.

40 2. A reflecting system including two plano-convex lenses, the convex faces of which are opposite each other, the plano face of one of the lenses being reflective and intersecting the principal axis of the system at the principal focus of the latter.

45 3. In a reflecting system, the combination of two discs of transparent material arranged in spaced parallel relation, each disc having on its

interior surface aligning convex faces, the outer face of one of the discs being silvered.

4. In a reflecting structure, the combination with two discs of transparent material, said discs being spaced from each other, each disc having on its inner face a series of bosses forming converging lenses, the lenses on the one disc being opposite the lenses on the other disc, and the outer face of one of the discs intersecting the principal axes of the systems formed by the 10 several pairs of lenses at approximately the principal focal points of such systems and being silvered.

5. In a reflecting system having a focus, a pair of cooperating convex lenses of identical form 15 arranged in axially aligned spaced relation and a reflector on one of said lenses lying in a plane which intersects the axis of the system at the focus.

6. In a reflecting system a pair of plano-convex lenses of identical form arranged in axially aligned spaced relation with their convex faces toward each other and a reflector on the plane face of one of said lenses, said reflector intersecting the axis of the lens at the point where 25 parallel light projected onto the plane face of the opposite lens is brought into a focus.

7. In a reflecting structure a pair of transparent plates, means to retain the plates in spaced parallel relation, lenticular bosses on the 30 adjacent faces of each plate, the axes of the bosses on one plate aligning with those of the bosses on the other plate and a reflecting coating on the smooth face of one of the plates.

8. In a reflecting structure a pair of disks of 35 transparent material, one disk being the counterpart of the other, each of said disks having bosses on one face forming converging lenses, flanges at the edges of the disks for holding them in spaced parallel relation with the bosses facing one another and in axial alignment and a silvered surface on the plane face of one of the disks.

HENRY PHELPS GAGE.
